(57) CLAIM

The ornamental design for a foldable handheld fan, as shown and described.

DESCRIPTION

FIG. 1 is a first perspective view of a foldable handheld fan showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is a perspective view of the foldable handheld fan in the folded state.

The broken lines in the drawings depict portions of the foldable handheld fan that form no part of the claimed design.
